UNITED STATES PATENT OFFICE.

PETER A. SCHAEFER, OF GREENSBURG, PENNSYLVANIA.

MAGNETO CONTACT.

Application filed March 1, 1922. Serial No. 540,262.

To all whom it may concern:

Be it known that I, PETER A. SCHAEFER, citizen of the United States, residing at Greensburg, in the county of Westmoreland and State of Pennsylvania, have invented 5 certain new and useful Improvements in Magneto Contacts, of which the following is a specification.

This invention relates to an improved 10 magneto contact for Ford motor cars and seeks, as one of its principal objects, to provide a contact which may be easily and quickly removed or replaced so that the contact may, at any time, be conveniently 15 cleaned.

The invention has as a further object to provide a contact embodying a gasket for preventing the loss of oil through the plug opening in the transmission cover of the 20 vehicle and wherein the gasket will be yieldably fed to a position sealing the opening.

And the invention has as a still further 25 object to provide a contact which may be readily substituted for the usual magneto contact of a Ford car without the necessity for any structural change in the car.

Other and incidental objects will appear 30 hereinafter.

30 In the drawing:

Figure 1 is a fragmentary sectional view 35 showing my improved contact in connection with the transmission cover and coil ring of a Ford car, the contact being shown in elevation.

Figure 2 is an enlarged vertical sectional 40 view through the contact.

Figure 3 is a transverse sectional view 45 on the line 3—3 of Figure 2, looking in the direction of the arrows, and

Figure 4 is a fragmentary sectional view 50 on the line 4—4 of Figure 3, looking in the direction of the arrows.

As is well known, the magneto of a Ford 55 car as now constructed is associated with the engine flywheel. A stationary ring of coils is employed and mounted upon the flywheel of the engine to revolve within said ring is a series of magnets. Current is thus generated in the coils and screwed upon the 60 transmission cover of the engine is a magneto contact to coact with a terminal upon the coil ring. The magneto contact very often becomes fouled while pieces of lint

and other foreign matter collect between 55 the contact and the terminal of the coil ring. It accordingly becomes necessary to remove the magneto contact from time to time and since, as previously noted, the contact is screwed to the transmission cover, 60 removal of the contact is tedious and inconvenient. The present invention, therefore, seeks to provide a contact eliminating these disadvantageous features. In the drawing, I have, for convenience, shown my 65 improved contact in connection with a conventional transmission cover 10 of a Ford car. The usual stationary ring of coils of the magneto of the car is indicated at 11 and between a pair of the coils of said 70 ring is mounted a terminal 12. Formed through the cover 10 above said terminal is an opening 13 to accommodate the customary magneto contact supplanted by the present invention.

In carrying the invention into effect, I employ a cylindrical bushing 14 which is formed to snugly fit through the opening 13 of the transmission cover and is provided at its upper end with a flange 15 overhanging the cover for supporting the bushing in position. Surrounding said flange is an appropriate gasket 16 and resting upon said gasket is a base ring 17. This ring may be of aluminum or other approved material 80 and is formed to register with the opening 13 in the transmission cover 10 overlying the flange 15 of said bushing. The ring is stepped and provided with a plurality of bosses 18 through which are formed suitable openings to accommodate screws 19 threaded into the usual openings in the cover for firmly connecting the ring therewith, the ring serving to clamp the bushing 90 14 therebeneath. Formed in the ring, as 95 best shown in Figures 3 and 4, is a plurality of spaced arcuate slots 20 opening through the upper face of the ring, while at their inner ends, these slots are provided with pockets 21. Freely fitting through the ring is a preferably aluminum shell 22, reduced at its lower end portion to loosely fit in the bushing 14, and provided with a beveled lower end edge 23. Projecting radially 100 thereabout are lugs 24 engaged in the slots 20 for securing the shell upon the base ring 105 and snugly, but slidably, fitting through

the shell is a tubular preferably fiber insulator 25. This insulator is closed at its upper end by an end wall 26, while at its lower end said insulator is provided with a radial 5 annular shoulder or flange 27 and clamped between said flange and the beveled lower edge 23 of the shell is a preferably felt gasket 28 projecting slightly beyond the periphery of the shell to engage the bush- 10 ing 14. Slidably fitting in the insulator at its lower end is a preferably brass contact point 29 provided at its upper end with a stud 30 and surrounding said stud to be freely received within the insulator is a 15 spring 31 preferably soldered to the stud. At its upper end, the spring carries a binding post 32 which freely fits through an opening in the end wall 26 of the insulator and is provided at its inner end with a head 20 33 to coact with said end wall. Formed on said head is a stud 34 fitting in the upper end of the spring and, preferably, the spring is also soldered to this stud so that the contact point 29 as well as the binding 25 post 32 will thus be permanently connected to the spring. Threaded upon the binding post to coact with the upper end of the insulator is a nut 35 and threaded upon said post to coact with this nut is a binding nut 30 36 for connecting a circuit wire, as conventionally illustrated at 37, with the binding post.

As will now be observed, the lugs 24 of the shell 22 will normally rest in the pockets 21 35 of the slots 20 of the base ring 17 for locking the shell upon the ring while the contact point 29 will be urged by the spring 31 to engage the terminal 12 of the coil ring 11. Accordingly, current may flow from said 40 terminal through the contact point 29, spring 31 and binding post 32, to the wire 37, the insulator 25 serving to insulate the contact point and associated parts with respect to the shell. Furthermore, as will be noted, 45 the gasket 28 will coact with the bushing 14 forming a sealed joint therewith and, as will be observed, the tension upon the spring 31, through being compressed by engagement of the contact point 29 with the terminal 12, 50 will be communicated to the insulator 25 for urging the insulator in a direction upwardly through the shell. Accordingly, the gasket will be compressed between the flange 27 of the insulator and the beveled shoulder 23 of the shell so that the tension of the spring in 55 conjunction with said shoulder will serve to expand or feed the gasket against the wall of the bushing for maintaining the joint between the gasket and bushing constantly 60 sealed. Leakage of oil through the bushing will thus be prevented, while, at the same time, the bushing will present a smooth surface to the gasket so that multilation or 65 stripping of the gasket will be prevented when the shell is displaced. As will be ap-

preciated, the shell may be removed by simply counter-rotating the shell to disengage the lugs 24 thereof from within the slots 20, when the shell may be lifted upwardly and displaced and, of course, by reversing this 70 operation, the shell may be replaced. I accordingly provide an arrangement wherein the contact point 29 and associated parts may be readily cleaned while access may be had to the upper end of the terminal 12 75 through the bushing 14 for cleaning the effective contact surface of said terminal.

Having thus described the invention, what is claimed as new is:

1. A contact including an annular base 80 member formed at its inner periphery with a slot having the greater portion of its length extending circumferentially of the member, the slot opening at one end through the upper face of said member and provided at its opposite end with a pocket, a shell coacting with the member and provided with a lug removably received within said slot to engage in said pocket locking the shell upon the base member, and a contact 90 point carried by the shell.

2. In a magneto contact for motor vehicles, the combination of a shell, a gasket associated with the shell, slidable means carried by the shell for compressing the gasket, an electrical conductor to engage a contact within a flywheel case and including a spring, and means for connecting the shell with said case holding said spring compressed urging the conductor in engagement 100 with said contact as well as urging said first mentioned means against the gasket to feed the gasket to a position operatively forming a joint between the shell and case 105 yieldably closed by said spring.

3. In a magneto contact for motor vehicles, the combination of a shell for connection with an element having an opening therethrough, a member slidable upon the shell, a gasket interposed between said member and the shell, and an electrical conductor including a spring tending when compressed to shift said member upon the shell against the gasket and feed the gasket against the wall of said opening forming a joint there- 115 with yieldably closed by said spring.

4. In a magneto contact for motor vehicles, the combination of a bushing, a shell associated therewith, a member slidable upon the shell, a gasket interposed between said 120 member and the shell, and an electrical conductor including a spring tending when compressed to shift said member upon the shell against said gasket and feed the gasket against the wall of the bushing forming a joint therewith yieldably closed by said spring.

5. In a magneto contact for motor vehicles, the combination of a shell for connection with an element having an opening 130

therethrough, a tubular insulator slidably fitting through the shell and provided at its lower end with a shoulder, a gasket interposed between said shell and the shoulder, and an electrical conductor extending within the insulator and including a spring tending when compressed to shift the insulator upon the shell for compressing the gasket between said shoulder and the shell and feeding the gasket to the wall of said opening 10 forming a joint therewith yieldably closed by said spring.

In testimony whereof I affix my signature.
PETER A. SCHAEFER. [L. s.]
